UNITED STATES PATENT OFFICE

172,741

COMBINED BUMPER FASTENER AND TOW BOLT FOR MOTOR CARS

Peter B. Cooper, Fairfield, Conn.

Application March 2, 1953, Serial No. 23,855

Term of patent 14 years

(Cl. D54—9)

To all whom it may concern:

Be it known that I, Peter B. Cooper, a citizen of the United States, residing at Fairfield, county of Fairfield, State of Connecticut, have invented a new, original, and ornamental Design for a Combined Bumper Fastener and Tow Bolt for Motor Cars, of which the following is a specification, reference being had to the accompanying drawing, forming a part hereof.

Fig. 1 is a side elevational view of a combined bumper fastener and tow bolt for motor cars, showing my new design;

Fig. 2 is a fragmentary edge view thereof, and Fig. 3 is an end view.

The dominant features of my design reside in the full line portions of the drawing.

I claim:

The ornamental design for a combined bumper fastener and tow bolt for motor cars, substantially as shown and described.
